UNITED STATES PATENT OFFICE.

THOMAS POWNALL FORD, OF LONDON, ENGLAND, ASSIGNOR TO THE AMERICAN ELEVATOR COMPANY, OF SAME PLACE.

HYDRAULIC LIFT.

SPECIFICATION forming part of Letters Patent No. 387,407, dated August 7, 1888.

Application filed January 5, 1888. Serial No. 259,888. (No model.)

To all whom it may concern:

Be it known that I, THOMAS POWNALL FORD, at present residing at 4 Queen Victoria Street, in the city of London, England, engineer, have 5 invented new and useful Improvements in Hydraulic Lifts, of which the following is a full, clear, and exact description.

My invention relates to that kind of hydraulic lift in which the cage is suspended by 10 a chain or rope passing round an overhead sheave and under a sheave carried at the upper end of the rod of a piston working in a vertical cylinder with a column of water above and below it, whereby the lift is actuated.

15 The invention relates, first, to the valve-gear for controlling the admission of the water to the main cylinder and its circulation from one end of said cylinder to the other; and it has for its object to enable plug or slide valves to 20 be used and at the same time prevent leakage of the water owing to grit preventing the valves being properly seated.

The invention consists in the combination, 25 with valves, of the plug or sliding type sustaining the bulk of the pressure from the supply and controlling the circulation of water from one end of the main cylinder to the other, of an auxiliary cup-leather valve which is operated concurrently with and by the same 30 hand rope-gear as the main valves. Cup-leather valves, which are not liable to leakage like metal valves, cannot, however, be used to the same advantage if exposed to high pressure, (say seven hundred pounds per square inch,) 35 such as it is proposed to use in this lift, as they are liable to be forced through and be cut in passing over the openings in their seats. In the combination of my invention the cup-leather valve is exposed when passing over the 40 ports in its seat only to a very diminished pressure, which is insufficient to injure the cup-leather valve, the office of this valve being merely to arrest any leakage that might occur at the main valves when all the valves are 45 closed.

The invention has, secondly, for its object to prevent the application of pressure to the under side of the piston in consequence of leakage, as well as to compensate for the difference of area of the two ends of the main cyl-

inder (due to the displacement of the piston-rod) by admitting low-pressure water to make up the deficiency when the water is circulated from the upper to the lower end of the cylinder.

55

My invention relates, thirdly, to an automatic regulator for checking the flow of water both on the ascent of the main cylinder under a light load or on its descent under a heavy load.

60

Reference is to be had to the accompanying drawings, forming part of this specification, wherein—

Figure 1 is an elevation, partly in section, of the main cylinder, circulating-pipe, and 65 valve-gear of a hydraulic lift of the class to which my invention relates. Fig. 2 is vertical section through the cup-leather valve separately. Fig. 3 is a vertical section of the regulator.

70

The same letters of reference indicate the same parts in all the figures.

The main valves A B, which may be of the conical-plug form, comprise a valve, A, controlling the water from the supply to what I 75 term a "circulation-chamber," C, and a similar valve, B, controlling the passage of water from the circulation-chamber C to the circulating-pipe D, that leads therefrom to the upper end of the main cylinder E, these two 80 valves A B being operated by gear from the hand-wheel rope passing through the car. F is a cup-leather piston-valve working within the circulation-chamber as a cylinder and controlling circulation, or by-pass orifices g, the 85 said valve being operated simultaneously with valves A and B through rack and pinion or other gear.

The valve-gear shown consists of levers a b, connected with the stems of valves A B, respectively, both levers being connected with the same rack-rod I, gearing with a pinion, i, on the axis of the pulley K, over which runs the hand-rope. The lever a is connected to the stem of valve A by a pin-and-slot connection, a', which permits of motion of the lever toward the valve A, although the latter has closed on its seat. The lever b is a bell-crank lever and is connected with the stem of valve B through a link, b', the center of motion, b², 90

95

100

of the lever being opposite the end of the valve, so that the latter will be closed on the lever-arm link and valve-spindle coming into line, and will be opened by angular motion of the lever either way from the position shown. The cup-leather piston-valve F is carried on a spindle, f, having rack-teeth on its upper end and gearing with a pinion, f', on the same axis with pinion i.

10 The operation is such that when the valve A from the supply is opened the valve B is also opened to admit water to the upper end of the main cylinder E, the cup-leather valve F being then raised wholly above the orifices 15 or ports g, which it controls, and when by motion in the opposite direction the valves A, B are closed and the valve B alone opened by the continued motion of lever b the cup-leather valve will be moved to the position shown in 20 Fig. 2, between the two sets of by-pass or circulation ports g g', which permit the water to circulate from the upper end of the main cylinder through pipe D, chamber C, by-pass g to pipe H, leading to the lower end of said 25 cylinder.

The invention consists, secondly, in keeping the exhaust-pipe H connected to the lower end of the main cylinder always open instead of closing it by a valve, as heretofore, so that were 30 leakage past the valves or main piston to occur when the cage is landed no pressure can be generated against the lower side of the main piston, which cannot, consequently, rise and throw the sheave off the ropes. The exhaust-pipe H discharges into an open tank, L, (as 35 near as possible at the level of the bottom end of the cylinder E,) into which the mouth of the pipe H dips below the level of water retained therein, so that the deficiency in volume of the 40 circulating water will be made up by water forced back by atmospheric pressure through the exhaust-pipe to the main cylinder.

The action of the regulator which forms the subject of the third improvement is due to the 45 inertia of the column of water itself. The regulator consists in a plunger-valve, N, Fig. 3, fitted to work in a cylinder in line with the column of water in the pipe D to be regulated, so that the latter will impinge directly against 50 the end of the plunger-valve. The cylinder is formed with by-pass passage O P, communicating with ports o p, controlled by the plunger, which acts as a balance-valve, controlling the flow of water transversely across the cylinder 55 from port o to port p, or vice versa. The plunger is held (by a weighted bent lever, R R', working on an axis, Q, or other equivalent

contrivance) in its normal or mid position, so as to give a full passage to the water; but on the water striking the end of the piston with 60 a velocity exceeding a predetermined limit the weight will be overcome and the plunger moved so as to check the flow of water at the ports o p, the action being similar in whichever direction the water is flowing. In Fig. 3 65 the water is supposed to be flowing in the direction of the arrow.

The motion of the plunger-valve would be limited by suitable stops, so that it shall never cut off entirely the passage of the water. In 70 the example shown the stops are formed by the arm R' of the weighted lever abutting against the top and bottom of the slot in the casting in which it moves.

Having now particularly described and ascertained the nature of the said invention and in what manner the same is to be performed, I declare that what I claim is—

1. In a hydraulic lift of the type specified, the combination, with water supply and circulation valves A, B of the plug or sliding type, and the chamber C, connected with the main cylinder, as described, of a cup-leather piston-valve, F, controlling the passage from chamber C to the lower end of the main cylinder and acting in conjunction with the valves A, B as a second seal to prevent leakage, both sets of valves being operated by the same gear, substantially as specified.

2. The combination, with the valves A, B, and F, of the rack-and-pinion gear and levers for operating such valves, and consisting of the piston rack-rod f, pinions f' and i, rack-rod I, and levers a b, connected to rack-rod I and to the stems of valves A B, substantially as shown 95 and described.

3. In a hydraulic lift, a double-acting regulator for checking both the supply and circulation of the water, and consisting of a plunger-valve, N, working in a cylinder interposed in 100 line axially of the column of water and provided with by-pass passages and ports O o P p, across which the valve works, said valve being combined with a weighted elbow-lever, R R', whereby the valve is held against the momentum of the water.

The foregoing specification of my improvements in hydraulic lifts signed by me.

THOMAS POWNALL FORD.
